UNITED STATES PATENT OFFICE.

BENJAMIN TAYLOR, OF MORRILLTON, ARKANSAS.

CAR-COUPING.

SPECIFICATION forming part of Letters Patent No. 289,172, dated November 27, 1883.

Application filed October 12, 1883. (No model.)

To all whom it may concern:

Be it known that I, BENJAMIN TAYLOR, of Morrillton, in the county of Conway and State of Arkansas, have invented a new and Improved Car-Coupling, of which the following is a full, clear, and exact description.

The invention consists in the construction of a draw-head having an upwardly and backwardly inclined slot in each side, through which slots a bolt is passed, which is held in the ends of a stirrup provided with suitable means for raising it. The draw-bar is provided with a recess in its top, whereby a head will be formed on each end of the draw-bar, which heads can catch automatically on the cross-bolts in the draw-heads.

Reference is to be had to the accompanying drawings, forming part of this specification, in which similar letters of reference indicate corresponding parts in both the figures.

Figure 1 shows two of my improved car-couplings, one being shown in longitudinal section and the other in longitudinal elevation, parts being broken out. Fig. 2 is an end view of a car provided with my improved coupling.

The draw-head A is provided with the usual longitudinal opening, A', and in each side with a short slot, B, which is inclined from the bottom to the top and from the front to the rear. A bolt, C, passes transversely through the draw-head and through the slots B. The ends of a stirrup, D, having an inverted-V-shaped top, are mounted on the ends of the bolt C. A rod, E, coupled to the top of the stirrup, passes through suitable guide-eyes on the end of the car, and extends up to the roof. Two levers, F, pivoted on the end of the car, extend to the sides of the same, and have their inner ends coupled to the top of the stirrup D. The draw-bar G has its ends beveled, and is provided in its top with a recess, G', extend-

ing to near the ends, and thereby forming a head, G², on the upper surface of the draw-bar at each end.

The operation is as follows: If the draw-bar is held in one draw-head and is inserted in the other, its beveled end will strike the bolt C in the latter, and will raise the same and will keep it raised until the head G² has passed; then the bolt C drops again and the cars are coupled, for if the bar G is drawn in the direction toward the outer end of the draw-head the inner ends of the hooks or heads G² catch on the bolts C. If the cars are to be uncoupled, the bolt C is raised by means of the rod E or the levers F. The draw-bar can then be withdrawn.

Having thus described my invention, I claim as new and desire to secure by Letters Patent—

1. The combination, with a draw-head having upwardly and backwardly inclined slots in the sides, of a bolt passed through the said slots and held in the end of a stirrup-frame provided with means for raising it, substantially as herein shown and described.

2. The combination, with a car, of the draw-head A, having upwardly and backwardly inclined slots in the sides, the bolt C, passed through the slots, the stirrup D, the rod E, and the levers F, substantially as herein shown and described.

3. The combination, with a car, of the draw-head A, having upwardly and backwardly inclined slots in the sides, the bolt C, the stirrup D, means for raising it, and the draw-bar G, provided in its top with a recess forming a head, G², at each end of the draw-bar, substantially as herein shown and described.

BENJAMIN TAYLOR.
